JOINT SYSTEM FOR TUBULAR FRAMEWORK OR SIMILAR METAL CONSTRUCTIONS

Application filed November 19, 1927, Serial No. 234,436, and in the Netherlands October 14, 1927.

Joint system for tubular metal constructions are already known, in which the tube ends at the joint are enclosed between two junction plates and are connected thereto by riveting or welding. The invention relates to a joint system of another type in which use is made of metal tubes, provided at one end or at both ends with flattened portions. In order to avoid the usual application of two junction plates, between which the tube ends are located, and moreover, in order to obtain a considerable saving of material, according to said type only a single junction plate is used and the connection of this plate to the tubes, is obtained by providing the flattened portions of said tubes with forks embracing the junction plate and the bottom of which abuts against one edge of said junction plate. It follows that the flattened portions in this construction are not enclosed between two junction plates but that a single junction plate is enclosed by the forked or slotted tube end portions. The connection is then finished by riveting or welding of the contracting surfaces. According to the present invention, in order to reinforce this kind of connection or joint, said forked or slotted end-portions of the tubes have U-shaped transversal profiles and are riveted to the corners of the junction plate so that a relative angular play of the junction plate and the tube is hereby avoided.

The slot of each fork is thus closed not only at its inner end or bottom, but also along one 35 of its sides and the closing wall at either side of the slot may be extended, so that reinforcing flanges are formed, whereby the flattened and slotted end portion of the tube obtains a T-shaped profile.

40 The invention will be explained more fully with reference to the drawings, showing an embodiment of the invention.

Fig. 1 is a front elevation of said embodiment of the joint system according to the invention, while

Fig. 2 is a cross section on the line II—II in Fig. 1.

In Figs. 1 and 2, 1 is a flat junction-plate having lateral edges 9 and a longitudinal edge 11, the two upper corners of said plate being enclosed by the flattened bifurcated opposite ends 3 of a pair of aligned tubes 5, each firmly secured to said plate by three rivets 7. The bottom 8 of each slot forming said bifurcated ends abuts against one lateral edge 9 of the plate 1, while the side wall of said slots of the aligned tubes 5 abuts against the longitudinal edge 11 of the plate 1.

Each of said side walls of the slots are extended beyond both sides of the flattened end of the tubes so as to form a reinforcing transversal flange 10, the profile of the tube end obtaining thereby the T-shape shown in Fig. 2. 6 indicates two tubes provided with known forks 4 embracing in the usual way 65 the lower part of the plate 1 and therefore abutting only on edge of said plate.

The illustrated T shape of tube ends may be obtained in a simple manner by means of punching machines, so that the new joint 70 system enables a strong and relatively inexpensive metal construction to be obtained.

Although only a particular embodiment of the connection according to the invention has been illustrated, it will be clear, that within 75 the spirit of the invention modifications are possible and, for instance, the flattened portion need not to be provided with the reinforcing flange 10, this depending upon the construction in which the connection is used. 80

What I claim is:

1. Joint system for tubular framework or similar metal constructions, comprising a tubular member, a polygonal junction plate, a slotted flat end on said tubular member forming two flat solid parallel walls embracing a corner of said junction plate and having U-shaped transverse and longitudinal profiles in order to abut two adjacent perpendicular 85 90

edges of said plate and rivets for securing the joint.

2. Joint system for framework or similar metal constructions, comprising a tubular member, a polygonal junction plate, a slotted flat end on said tubular member which forms two flat solid parallel walls embracing a corner of said junction plate and which have a U-shaped longitudinal profile and a **10** T-shaped transverse profile in order to abut two adjacent perpendicular edges of said plate and to reinforce the joint and rivets for securing said joint.

15 In testimony whereof I affix my signature.
ARIE VAN HATTUM.
